UNITED STATES PATENT OFFICE.

JOSEPH KRELL, OF BERLIN-PANKOW, GERMANY.

PRINTING PLATE AND THE LIKE.

Application filed September 27, 1926, Serial No. 138,042, and in Germany October 15, 1925.

My invention relates to printing plates and the like, for instance, of addressing machines, and it is an object of my invention to provide a readily detachable and exchangeable mark for an article of this kind.

To this end I subdivide the printing plate, etc., into a body and a plate, preferably of smaller size than the body, which constitutes the mark, and I connect this mark with the body by resilient means so that the mark is firmly attached to the body on the one hand but is readily detached and exchanged on the other.

In a preferred embodiment of my invention I subdivide the plate, etc., by a transverse parting line, fold over two parallel edges of the mark or the body so as to form two parallel grooves or pockets along these edges, and secure two springs or two pairs of springs to the parts without the grooves which are adapted to enter the grooves on the other part and, by their reaction, to hold the parts firmly together. When a longitudinal pull is exerted on the two parts they will readily separate.

The article according to my invention may be employed for instance for printing the names of employees in a shop. The name is then cut out or otherwise formed on the body of the article and an indication of the department of the shop in which the employee is engaged, is similarly formed on the mark. When the employee is transferred to another department the mark is exchanged.

I am not limited to any size or relative size of the mark and the body nor to any definite position of the parting line between the body and the mark. My invention relates to any size, shape, etc., of the parts and its essential feature is the resilient, firm and readily detachable connection between the two parts constituting the article. Its two parts are preferably of identical cross section and the unit which they constitute is similar to a normal, i. e., undivided plate or the like from which it is only distinguished by the almost imperceptible partition line.

In the drawings a printing plate for addressing machines is illustrated diagrammatically by way of example.

Fig. 1 is an elevation of the printing plate showing the body and the mark assembled,

Figs. 2, 3 and 4 are sections on the lines II-II and III-III of Fig. 1, respectively,

Fig. 3 being a section similar to Fig. 2 but showing only the upper edge of the body on a larger scale.

Fig. 5 is an elevation similar to Fig. 1 showing the parts separated.

Fig. 6 is a transverse section of the mark on the line VI-VI of Fig. 5,

Fig. 7 is a longitudinal section on the line VII-VII of Fig. 1,

Fig. 8 is a plan view viewed as indicated by the arrow VIII in Fig. 5.

Referring now to the drawings, *a* is the main part or body of the printing plate which is transversely subdivided, and *b* is its detachable mark. The longitudinal edges of both parts are folded over at *c* and *c'* so as to form parallel grooves or pockets *d* and *d'*. The sections of both parts are identical and the parts are only distinguished by the mark *b* being shorter than the main part or body *a*. *e* and *f* are laminated springs inserted in the grooves or folded-over edges *c*, *c'* of the body *a*, and *c''* are depressions in the folded-over ends of the body by which the springs are held. Obviously, any other method of securing the springs in their groove might be employed. The projecting ends of the springs are bent slightly apart as shown in Fig. 8. I am not limited to a definite number of springs and it will be understood by those skilled in the art that a single spring might also perform the function desired.

The depth of the springs is substantially equal to that of the groove *d* and their length is substantially equal to the length of the mark *b* but obviously the dimensions of the springs may be varied as desired.

When a mark is to be attached to a body the mark *b* is pushed against the body *a* and the springs *e*, *f* will then enter the grooves at the edges *c*, *c'* of the mark and, by their reaction, hold the mark firmly to the body as shown in Fig. 1. At the same time, the mark is readily removed for exchanging when a longitudinal pull is exerted on the mark and the body.

The article is similar to the ordinary undivided plates the partition lines which have been shown slightly apart for the sake of clearness in Fig. 1, constituting in fact a single line.

In the present instance, the body *a* bears the name of an employee, for instance, a turner, and the mark bears the reference letter of his department, A, with the numeral index 5. When the man is transferred to

another department the body remains unaltered but the mark "A5" is exchanged for that of the new department, say, "F3".

Instead of a letter and an index, as shown, 5 the mark may obviously bear any other indication, for instance, a coloured plate, a symbol, etc.

I claim:

10 A printing plate for addressing machines and the like, including main and detachable

parts of equal cross sectional width, pairs of springs carried by and projecting from the edges of the main part, the springs of each pair engaging one another, and guides carried by the detachable part receiving the 15 pairs of springs and frictionally coacting therewith to maintain the detachable part in position.

In testimony whereof I affix my signature.
JOSEPH KRELL.
